UNITED STATES PATENT OFFICE.

EDGAR B. SYMONS, OF WINNETKA, ILLINOIS, ASSIGNOR TO SYMONS BROTHERS COMPANY, OF WINNETKA, ILLINOIS, A CORPORATION OF SOUTH DAKOTA.

CRUSHING-MACHINE.

1,256,843.

Specification of Letters Patent. Patented Feb. 19, 1918.

Application filed July 19, 1916. Serial No. 110,030.

To all whom it may concern:

Be it known that I, EDGAR B. SYMONS, a citizen of the United States, residing at Winnetka, in the county of Cook and State 5 of Illinois, have invented a certain new and useful Improvement in Crushing-Machines, of which the following is a specification.

My invention relates to improvements in crushing machines, and has for one object 10 to provide a new and improved form of crushing machine which will be simple in construction, easy to assemble, light in weight, and which will be long lived and will require a minimum of power to operate 15 it. Other objects of my invention will appear from time to time throughout the specification.

My invention is illustrated more or less 20 diagrammatically in the accompanying drawings, wherein—

Figure 1 is a vertical section through my machine;

Fig. 2 is a section along the line 2—2 of 25 Fig. 1;

Fig. 3 is a section along the line 3—3 of 30 Fig. 1;

Fig. 4 is a section along the line 4—4 of 35 Fig. 3;

Fig. 5 is a section along the line 5—5 of 40 Fig. 1;

Fig. 6 is a plan view of the central portion of one of the crushing disks; showing 45 modified form.

Fig. 7 a section along the line 7—7 of 50 Fig. 6.

Fig. 8 is a section along the line 8—8 of 55 Fig. 3.

Like parts are indicated by like characters 60 in all the drawings.

A is the first base plate adapted to be 65 supported on any suitable foundation not here specifically illustrated. This plate carries near its outer edge, a cylindrical wall A¹. This wall has at one point an out- 70 wardly extending portion A² which carries the bearing A³. In this bearing is rotatably 75 mounted the horizontal drive shaft A⁴. The outer end of the bearing A³ carries oil rings A⁵, which coöperate with a sleeve A⁶ on 80 the shaft A⁴ to prevent egress of oil from the housing or ingress of dust and grit thereto. This shaft is adapted to be rotated by power applied from any suitable source 85 to the belt wheel A⁷ keyed to the end of the

shaft. A⁸ is a cylindrical foundation wall 55 projecting upwardly from the base A inside of and concentric with the wall A¹. This carries at one point the bracket A⁹ which supports a bearing A¹⁰ for the inner end of the shaft A⁴. This wall A⁸ is apertured at 60 A¹¹ beneath the bracket A⁹ to permit a free circulation of oil throughout the chamber formed by the base A and the wall A¹.

B is a supporting plate resting on the 65 wall A⁸ and bolted to the flanges B¹ on the wall as indicated. Centrally disposed in this plate B is a rigid stationary guide sleeve B² braced by the webs B³. Rotatably mounted within the sleeve B² is an eccentric sleeve B⁴, there being anti-friction bearing 70 surfaces interposed between the upper and lower ends of the eccentric sleeve and the fixed sleeve B². The eccentric sleeve has at its lower end, a miter gear B⁵ in mesh with a miter gear B⁶ keyed to the inner end of 75 the shaft A⁴, the plate B being cut away as shown to permit the two gears to engage. The weight of this sleeve is carried by friction bearing segments B⁷ between removable plates B⁸, B⁹ pinned respectively to the boss 80 B¹⁰ on the base A, and to the lower side of the hub B¹¹ of the miter gear B⁵.

C is an annular track supporting wall 85 rigidly mounted on the annular rib C¹ on the plate B immediately above the wall A⁸. The wall C is cut away at C² over the bearing A¹⁰. This wall carries a track C³ upon which travels a series of bearing rollers C⁴ held in radial position by a floating collar C⁵. Resting upon these rollers is a floating 90 track C⁶. It will be noted that these roller bearings have cylindrical bearing surfaces, divided into two zones, the outer being of greater diameter than the inner, and that the tracks have two separate, annular bearing surfaces engaging the roller zones at different levels, thus giving the same general effect as is given by the conical rollers of the usual type of thrust bearing, without the tendency in that type toward squeezing 95 out of the tapered roller from between the track surfaces. This ring C⁶ carries an oil trough C⁷ which feeds oil to the bearings upon which the rollers are mounted through a duct C⁸.

D is a rotating supporting plate. It is provided with an annular downwardly extending flange D¹ resting on the track C⁶

- so that the plate is supported on the main frame by means of the tracks and the roller bearing. Fingers D² extend down from the rotating plate and pins pass through the 5 ends of these fingers and the track C⁶ to hold them together. D³ is a sleeve extending downwardly from the rotating plate and in rotary engagement with the fixed sleeve B² whereby the plate D is centered, 10 supported and guided. Extending downwardly from the outer periphery of the plate is an annular flange D⁴. This annular flange D⁴ carries a gear D⁵ on the inside adjacent its lower edge, which gear is in 15 mesh with a miter pinion D⁶ keyed to the shaft A⁴. The extreme lower edge of the flange D⁴ terminates in an inner and outer annular flange D⁷, D⁸ respectively, one on the outside, the other on the inside of the 20 upper edge of the wall A¹, which wall A¹ is notched or cut away as at D⁹ to assist in preventing egress of oil and ingress of dust. The upper surface of the plate D is recessed as indicated, the bottom of the 25 recess being substantially flat and horizontal, the side wall being drawn about a sphere so as to provide a spherical guide bearing or guide surface D¹⁰.
- E is a ball wedge. It is as shown, a 30 relatively thin lenticular plate having on the bottom an annular flat bearing surface E¹, resting on the plate D, and at the top a curved spherical bearing surface E². This upper part of the wedge is provided 35 with a central depression. The shaft E³ extends downwardly from the center of the ball wedge, and is in rotatable engagement with the hollow interior portion of the eccentric sleeve B⁴, there being a babbitted 40 bearing E⁴ for that purpose. The shaft E³ is hollow and the hollow pipe or passage extends clear up through the ball wedge as indicated at E⁵. E⁶ is a tilting plate. It has a spherical surface to engage the spherical 45 surface E² and rests thereupon. It also has spherical surfaces E⁷ in engagement with the spherical surfaces D¹⁰. Resting upon the upper flat surface of this plate E⁶ is a removable crushing disk E⁸.
- 50 Arranged about the outer periphery of the plate D, overhanging the flange D⁴, is an annular flange F, which has arranged at spaced intervals thereabout, the bosses F¹, integral with the plate D. These bosses 55 are bored out to hold the pins F², which are provided with enlarged portions F³ above the upper surface of the bosses and are screw-threaded at their lower ends whereby the nut F⁴ may be used to draw them 60 down into position. F⁵ is a dust or guard plate resting on the upper surface of the plate D, near its periphery, and this dust plate is provided with a rib F⁶ engaging a groove F⁷ in the plate D.
- 65 The outer edge of the plate F⁵ has a

downwardly extending cylindrical flange F⁸. The inner edge has an upwardly extending cylindrical flange F⁹, which projects up between the edge of the tilting plate E⁶ and the guard ring F¹⁰ carried 70 thereby. The plate F⁵ is provided with the bosses F¹¹ surrounding each of the pins F² and resting on the bosses is an auxiliary dust catching plate F¹² which projects outwardly beyond the pins F² and inwardly 75 to just clear the ring F¹⁰.

G is a sleeve mounted on the pins F² and resting upon the plate F¹². Resting upon the sleeve G is an annular ring G¹ having a lip G² extending outwardly away from 80 the sleeve G. G³ is a spring pressed heavy annular collar resting upon the ring G¹, its inner wall being screw-threaded at G⁴. Springs G⁵ rest upon the collar G³ and contact at their upper ends the ring G⁶, which ring is also mounted on the pins F², but this ring unlike the collar G³ is not free to move. It has an annular wall G⁷ extending down and resting upon the ring G¹. The pins F² extend up through it and the 90 nuts G⁸ are tightened up to hold this collar rigidly in position so that the collar G³ may rise if the springs are compressed, while the remainder of the structure remains in fixed position.

H is an adjusting disk plate. It has about its periphery an upwardly extending screw-threaded flange H¹ in screw-threaded engagement with the collar G³. This plate H is upwardly coned and has mounted on its 100 under side the conical crushing disk H² held in position by the collar H³, and engaging the disk at its inner periphery and in screw-threaded engagement with a nut H⁴ on the upper surface of the disk H. This conical 105 disk as shown, terminates in a substantially flat annular ring which normally is but very slightly inclined to the disk E⁶ at its periphery. The part H¹ has an outwardly extending flange H⁵ overhanging the screw-threaded parts G⁴, and an annular protecting ring H⁶ hangs downwardly therefrom in slidable engagement with a part of the rings G³ to protect the screw threads. H⁷ are set screws in the flange H⁵ adapted to 110 engage the ring G³ to lock the parts against rotation and insure that the screw-threaded adjustment once made will remain constant. Projecting upwardly above the flange H⁵ are a series of cylindrical lugs H⁸. These 120 lugs are as shown in Fig. 2, provided for the purpose of manipulating this collar and rotating it to make the adjustment of the crushing disks toward and from one another. Turn buckles H⁹, having at either 125 end eyes H¹⁰, are used. One eye would be placed over one of the pins F², the other over one of the lugs H⁸. By this means pressure may be exerted to rotate the parts with respect one to the other. In the po- 130

sition shown in Fig. 2, however, the turn buckles are working against one another and have been tightened up to hold the parts against rotation in their locked position.

- 5 In Fig. 3 is shown part in plan and part in section, the chute which catches the material after it is crushed and discharges it to a suitable source of storage or discharge. J is an annular inner wall of varying depth.
- 10 The upper edge about its entire periphery comes up immediately under the overhanging part F⁸. The height of the wall varies because it always terminates just at and in engagement with the inclined chute bottom J¹. This inclined bottom comes to the upper apex J² of the diametrically opposed sides of the machine. From both sides of each apex it slopes very sharply down for a quarter of a revolution to a low point J³.
- 15 20 where it discharges into chutes J⁴ on opposed sides. The outer wall of the hopper J⁵ projects up above the wall to a point substantially level with the crushing disk E⁸. and is provided with a thick heavy reinforcing part J⁶ upon which the material discharged by centrifugal force from the crushing zone will be impinged. This inner reinforcing part is removable so that as the discharge of the material wears it can
- 25 30 be replaced without replacing the entire housing. The annular ring J⁷ extends up from the wall J⁵ to a point above the discharge from the crushing zone where is provided an annular ring J⁸ extending inwardly toward the ring G¹ and overhanging it so as to prevent rise of dust or other particles into the other part of the machine. Still above the part J⁸ is a cylindrical wall J⁹. this wall carrying a floor J¹⁰. The hopper J¹¹ extends down from the floor and discharges into the crushing zone through the ring H³, and material to be crushed is placed upon this floor and then fed through the hopper in the usual way.
- 35 40 45 The central part of the plate E⁶ is hollowed out at K and projecting out radially from this hollowed out part K are pockets K¹. These pockets K¹ are larger at the bottom than at the top so that the bolt head K² may be contained therein while the bolts K³ extend up through the narrow portion of the pockets. K⁴ is a filler disk located in and partially overhanging the crushing disk E⁸ by means of the coöperating flanges K⁵, K⁶. The bolts K³ extend up through this disk, and nuts K⁷ are screw-threaded on them to clamp the disk down to lock the crushing disk in position. In my preferred form a conical guard K⁸ rests on the small disk K⁴ and protects the upper ends of the screw bolts and the nuts, so that material which is to be crushed or material from the crushing zone will not fill in about these fastening members, and thus they can
- 50 55 60 65 always be detached. In the modified form

shown in Figs. 6 and 7, the central disk K⁹ is provided with a series of more or less triangular apertures as shown, and the circular disk K¹⁰ closes them covering the bolt heads. The disk is channeled or grooved 70 or cut away at K¹¹ and a cotter pin K¹² passes through a projection K¹³ and holds the disk in position.

It will be evident that while I have shown in my drawings an operative device, still 75 many changes might be made both in size, shape and arrangement of parts without departing from the spirit of my invention, and I wish therefore, that my drawings be regarded as in a sense diagrammatic. 80

On one side I have shown an arrangement wherein the upper sharply inclined portion of the discharge chute is cut away. Doors are provided in the walls of the housing on either side so that the operator may 85 by opening them get into the space inside so as to remove the nuts to take off the upper part of the crushing head. When the machine is in operation material will be deposited upon this flat surface and will assume the proper angle of inclination for the discharge of material into the discharge opening, that is to say, the material makes its own float.

The use and operation of my invention are 95 as follows:

As the material which has been crushed is discharged by centrifugal force violently from between the crushing plates, most of it passes clear out to be discharged into the 100 surrounding hood. A certain portion, however, will strike upon the sleeves surrounding those bolts which hold the disks together; such material will rebound and strike against the flange projecting outwardly from the tilting plate. Some of this material will again be discharged by centrifugal force, the remainder will drop down and be discharged beneath the annular plate. This discharge will be induced 105 partially by a current of air, which current of air is set up by the sleeves surrounding the holding pins acting as a centrifugal fan; the result is no dust can possibly pass up beneath the flange on the tilting disk to 110 115 enter the oiling system.

The material which is thus discharged, when it finds its way out into the dust hood, will be discharged by gravity in two directions on opposite sides of the machine, owing 120 to the steepness of the floor of the chute. This housing above the chute where the material strikes its walls is reinforced by a removable strip which may be replaced when wear makes this necessary. 125

The upper crushing disk is spring held, a large number of these springs being provided about the periphery, so that if the machine is overloaded, or if particles which cannot be crushed get into it, the springs will give 130

permitting the crushing plate or disk to rise without breaking of any part of the machine. There is a large number of these springs and their power is very great, and in order that the crushing plate may be adjusted or replaced without going to the trouble of taking out and tightening up each of these springs, means are provided for holding a screw threaded ring in position on one side of the springs and a holding ring on the other; thus making an assembly which may be removed or replaced without changing the tension in the springs. This may be done by merely loosening the nuts at the lower ends of the holding bolts, when the entire assembly consisting in the plate supporting apparatus, including springs, adjusting devices, dust guards, etc., may be removed as a unit without in any way changing the positions of the parts with respect to one another, the crushing plate may be removed from the assembly and a new plate put in place and the parts then returned to their original positions without any change in adjustment or arrangement taking place.

For the purpose of adjusting the distance between the crushing plates the upper plate is carried on a member screw-threaded in position, and set screws are provided for locking this member against rotation. Such a set screw lock is not always sufficient, and turn buckles with eyes at either end are provided, one eye going over a pin on the crushing plate carrier, the other over a part (in this case one of the holding bolts) on the spring anchor ring. For turning the screw threaded part to adjust the plate these turn buckles are all arranged to pull in the same direction. For locking the plate against rotation some of them are changed so that they pull in opposite directions; thus, when they are tightened up, no rotation is possible in either direction.

The rotating base plate is supported on a roller thrust bearing which is adjacent to the outside of the rotating plate at a point far removed from the center of rotation. The upper track of this roller bearing is loosely pinned to the under side of the rotating plate for convenience in assembly. The plate itself is rotatably mounted on and centered and guided by the upper end of fixed sleeve; which contains on its inside a bearing for the eccentric sleeve which actuates the wedge plate. This sleeve is stiffened by a series of webs, projecting upwardly and inwardly from a flange which rests on a foundation wall in the bottom of the housing and carries the sleeve.

The eccentric sleeve is supported at the bottom on a friction thrust bearing, and is rotated by a miter gear on the drive shaft in mesh with a similar gear on the sleeve. The rotating head itself is driven by a miter

pinion in engagement with a miter gear on the lower edge of an annular ring extending down from the outer periphery of the rotating plate.

The lower flat crushing disk is held in position by a collar overlying a portion of the disk; the holding bolts may easily be slipped in position in the support before the collar is placed. When the nuts on the holding bolts have been tightened up a suitable cover is applied to prevent entrance of fine material into the pocket, which would interfere with the action of the holding bolt.

Since the wear on the crushing disk is very great, and they must frequently be removed, it is essential to provide convenient means for removing the upper crushing head assembly so that access may be had to the disks. The upper head is held in position by a large number of holding bolts, and in order that the operator may have access to the nuts holding them for removal the upper portion of each side of the discharge chute is cut away. Doors are provided on either side of the housing so that the operator, by opening these doors, may have access to the space immediately inside the chute where these nuts are located; thus ample room is provided for unscrewing these nuts to permit the removal of the upper half of the crushing head.

I have used the term "crushing head" as applied to the place where the crushing is done. This crushing head consists in a rotating base plate, which is guided by a bearing on a central fixed sleeve, and supported by roller thrust bearing adjacent to the periphery, thus preventing tipping and making a solid foundation. A crushing disk is mounted on a tilting plate supported in a truncated, spherical bearing on the rotating base plate. The lenticular wedge plate, interposed between the rotating base plate and the tilting plate, is gyrated by an eccentric sleeve rotating inside the fixed sleeve, and containing the shaft which depends downwardly from the wedge plate.

The rotating base plate, together with the tilting plate and a crushing disk on the tilting plate form what is in effect the lower half of the crushing head. This lower half is fixed in position, though free to rotate. The upper half of the crushing head is not only mounted upon the lower half, but removable therefrom. This upper half consists in an anchor ring rigidly held down on the rotating base plate, a floating ring mounted free to move axially with respect to the anchor ring, and yieldingly held against movement, away from the lower part of the crushing head, by a series of powerful springs under compression, and an adjusting plate screw threaded in the anchor ring and carrying an upper crushing disk. The adjusting plate may be rotated in its screw

threaded engagement to move the upper crushing disk toward and from the lower, and means are provided for locking it against rotation so that an adjustment once 5 made is for operative purposes permanent.

The holding pins which tie the parts of the crushing head together have shoulders intermediate their ends and nuts at their upper ends clamp all the parts of the upper half 10 of the head together as a unit against such shoulders. The nuts at the lower end, when the parts are in position, lock the upper half of the crushing head in position in respect to the lower half. If the upper nuts are released 15 the upper half of the head may be disassembled. If the lower nuts only are released the upper half of the head may be removed as a unit, and thus the interior of the crushing head will be open for cleaning or 20 for removal of the crushing plates.

I claim:

1. In a crushing machine a crushing disk, a supporting plate therefor, both of them being centrally apertured, a plug located within 25 and snugly fitting both apertures and having a flange overlying the portion of the crushing disk, and separate means for drawing the plug longitudinally toward the supporting plate to clamp the disk against the 30 plate.

2. In a crushing machine a crushing disk, a supporting plate therefor, both of them being centrally apertured, a plug located within 35 and snugly fitting both apertures and having a flange overlying the portion of the crushing disk, and means for drawing the plug longitudinally toward the supporting plate to clamp the disk against the plate, said means comprising bolts in engagement 40 with the plug, pockets in the side walls of the apertured plates containing the bolts, and nuts on the bolt ends in engagement with the plug, the heads of the bolts being held against longitudinal movement within 45 said pockets.

3. In a crushing machine a crushing disk, a supporting plate therefor, both of them being centrally apertured, a plug located within 50 and snugly fitting both apertures and having a flange overlying the portion of the crushing disk, and means for drawing the plug longitudinally toward the supporting plate to clamp the disk against the plate, said means comprising bolts in engagement 55 with the plug, pockets in the side walls of the apertured plates containing the bolts, and nuts on the bolt ends in engagement with the plug, the heads of the bolts being held against longitudinal movement within 60 said pockets, the plug being pocketed to engage and contain the nuts, and removable means for closing such pockets carried by the plug.

4. In a crushing machine a crushing disk, 65 a supporting plate therefor, both of them be-

ing centrally apertured, a plug located within and snugly fitting both apertures and having a flange overlying the portion of the crushing disk, and means for drawing the plug longitudinally toward the supporting 70 plate to clamp the disk against the plate, the supporting plate being provided with a centrally disposed pocket smaller in diameter than and in line with the central aperture, bolt engaging slots having open sides 75 communicating with such pocket said slots being enlarged toward the bottom, the plug holding means comprising bolts whose heads engage such enlarged slot portions and whose shanks lie in such slots, the bolts being held by engagement with the slots against longitudinal movement, and being held only by their engagement with the plug against transverse movement.

5. The combination with a rotary chamber 85 having an annular discharge opening about its periphery, of a housing inclosing such discharge opening, the bottom floor of the housing being divided into a plurality of sharply inclined panels terminating at their 90 lower extremities in a discharge chute.

6. The combination with a rotary chamber having an annular discharge opening about its periphery, of a housing inclosing such discharge opening, the bottom floor of the 95 housing being divided into a plurality of sharply inclined panels terminating at their lower extremities in a discharge chute, such panels being joined at their upper extremities by short flat surfaces below the discharge opening.

7. The combination with a rotary chamber having an annular discharge opening about its periphery, of a housing inclosing such discharge opening, the housing having concentric walls, one of the walls being outside of and projecting both above and below the discharge opening, the other being an inner wall and terminating below the opening, means for preventing discharge of material 105 down inside the inner wall.

8. The combination with a rotary chamber having an annular discharge opening about its periphery, of a housing inclosing such discharge opening, the housing having 115 concentric walls, one of the walls being outside of and projecting both above and below the discharge opening, the other being an inner wall and terminating below the opening, means for preventing discharge of material 120 down inside the inner wall, the bottom of the housing being formed of inclined panels joined at their upper extremities by short flat surfaces, doors in the walls of the housing immediately above such short flat 125 surfaces and in register one with the other.

9. A crushing machine comprising a housing, operating mechanism therein, a crushing head closing the housing and containing a crushing chamber, and means for 130

preventing the entrance of solid particles from the crushing chamber into the housing.

10. A crushing machine comprising a housing, operating mechanism therein, a crushing head closing the housing and containing a crushing chamber, and means for preventing the entrance of solid particles from the crushing chamber into the housing, said means comprising interlocking flanged rings, one on the head, the other on the housing.

11. A crushing machine comprising a housing, operating mechanism therein, a crushing head closing the housing and containing a crushing chamber, and means for preventing the entrance of solid particles from the crushing chamber into the housing, said means comprising interlocking flanged rings, one on the head, the other on the housing, and an annular plate parallel with the line of discharge from the chamber located intermediate the flanged gears and surrounding the rings.

12. A crushing machine comprising a housing, operating mechanism therein, a crushing head closing the housing and containing a crushing chamber, and means for preventing the entrance of solid particles from the crushing chamber into the housing, said means comprising interlocking flanged rings, one on the head, the other on the housing, and an annular plate parallel with the line of discharge from the chamber located intermediate the flanged rings and surrounding the rings, said plate being mounted on and adapted to rotate with the head.

13. A crushing machine comprising a housing, operating mechanism therein, a crushing head closing the housing and containing a crushing chamber, and means for preventing the entrance of solid particles from the crushing chamber into the housing, said means comprising interlocking flanged rings, one on the head, the other on the housing, and an annular plate parallel with the line of discharge from the chamber located intermediate the flanged rings and surrounding the rings, and means for producing a radial current of air outwardly along both sides of said plate, and particularly beneath it.

14. In a crushing machine, a crushing disk, a plate upon which it is rigidly mounted, a support for such plate, yielding means for holding the plate against movement within the support, and means for removably anchoring the support in position in the crushing machine.

15. In a crushing machine, a crushing disk, a plate upon which it is rigidly mounted, a support therefor, and yielding means for holding the plate in fixed position with respect to the supports, the plate, the sup-

ports, the disk and yielding means being mounted as a unit in the crushing machine.

16. In a crushing machine, a crushing disk, a plate upon which it is rigidly mounted, a support therefor, and yielding means for holding the plate in fixed position with respect to the supports, the plate, the supports, the disk and yielding means being mounted as a unit in the crushing machine, and means for holding them together in fixed position independent of their position with respect to the crushing machine.

17. In a crushing machine, a two part crushing head, a fixed crushing disk mounted upon one part of the head, a crushing disk spring held in the other part of the head, the latter part of the head being mounted and attached to the first part and removable therefrom as a unit without interfering with the adjustment of the crushing disk with respect thereto.

18. A crushing machine having a crushing disk, a plate upon which it is mounted, a ring in which the plate is screw-threaded, a support, the ring being slidably mounted in the support, yielding means for holding the ring against movement within the support, and means for holding the support together.

19. A crushing machine having a crushing disk, a plate upon which it is mounted, a ring in which the plate is screw-threaded, a support, the ring being slidably mounted in the support, yielding means for holding the ring against movement within the support, and means for holding the support together, and means for supporting the disk, the plate, the ring and the associate parts all as a unit in the crushing machine.

20. A crushing machine having a crushing disk, a plate upon which it is mounted, a ring in which the plate is screw-threaded, a support, the ring being slidably mounted in the support, yielding means for holding the ring against movement within the support, and means for holding the support together, and means for supporting the disk, the plate, the ring and the associate parts all as a unit in the crushing machine, such parts being removable from the crushing machine as a unit without changing their relative position.

21. A crushing machine having a crushing disk, a supporting plate therefor, a base upon which the plate is mounted, a sleeve extending upwardly from the base and in engagement with the plate to center it, and means adjacent the periphery of the plate for supporting it and guiding it.

22. A crushing machine comprising a rotating crushing head, a plate forming the bottom of the head, a wall downwardly depending from the periphery of the plate, a

- roller bearing located within the wall beneath the plate, and a guide member upon which the plate is rotatably mounted within the bearing.
- 5 23. A crushing machine comprising a rotating crushing head, a plate forming the bottom of the head, a wall downwardly depending from the periphery of the plate, a roller bearing located within the wall beneath the plate, and a guide member upon which the plate is rotatably mounted within the bearing, the guide member comprising a fixed rigid upwardly projecting sleeve, a larger sleeve downwardly projecting from the plate and inclosing it.
- 10 24. A crushing machine comprising a rotating crushing head, a plate forming the bottom of the head, a wall downwardly depending from the periphery of the plate, a roller bearing located within the wall beneath the plate, and a guide member upon which the plate is rotatably mounted within the bearing, the guide member comprising a fixed rigid upwardly projecting sleeve, a larger sleeve downwardly projecting from the plate and inclosing it, an eccentric disk slidably mounted on the top of the plate, an eccentric sleeve within the fixed sleeve and a driving pin extending down from the disk into the interior of such eccentric sleeve.
- 15 25. In a crushing machine a substantially fixed support, a crushing disk mounted thereupon, a second crushing disk in opposition to the first disk, and a support therefor, a collar normally fixed in position with respect to the main support in which one of the crushing disk supports is screw-threaded, means for rotating said support to change the position of the disk with respect one to another, said means comprising pins projecting upwardly from the supports and from the disk, turn buckles having eyes engaging their pins and adapted to move the parts and hold them in position.
- 20 26. In a crushing machine a cylindrical housing a bearing sleeve therein an eccentric sleeve mounted for rotation within and a carriage for rotation upon such bearing sleeve and a wall on the carriage in register with the cylindrical wall of the housing adapted to coöperate with it to close the housing.
- 25 27. In a crushing machine a cylindrical housing, a bearing sleeve therein, an eccentric sleeve mounted for rotation within and a carriage for rotation upon such bearing sleeve and a wall on the carriage in register with the cylindrical wall of the housing adapted to coöperate with it to close the housing, a crushing head mounted on the carriage and means responsive to the rotation of the carriage and the eccentric sleeve for crushing material within the crushing head and discharging it therefrom.
- 30 28. In a crushing machine a cylindrical housing, an inner flange concentric therewith, a plate carried by the flange and a central bearing sleeve mounted thereon, an eccentric sleeve mounted for rotation within and a carriage mounted for rotation upon the bearing sleeve, a downwardly extending wall on the carriage adapted to interlock with the wall of the housing and to close the housing.
- 35 29. In a crushing machine a cylindrical housing, an inner flange concentric therewith, a plate carried by the flange and a central bearing sleeve mounted thereon, an eccentric sleeve mounted for rotation within and a carriage mounted for rotation upon the bearing sleeve, a downwardly extending wall on the carriage adapted to interlock with the wall of the housing and to close the housing, a crushing head mounted on the carriage and means responsive to the rotation of the carriage and the eccentric sleeve for crushing material within the crushing head and discharging it therefrom.
- 40 30. In a crushing machine a cylindrical housing, an inner flange concentric therewith, a plate carried by the flange and a central bearing sleeve mounted thereon, an eccentric sleeve mounted for rotation within the bearing sleeve and a thrust bearing supporting it, a carriage mounted for rotation upon the sleeve supported by the plate and having a downwardly extending wall adapted to interlock with the housing wall to close the housing.
- 45 31. In a crushing machine a cylindrical housing, an inner flange concentric therewith, a plate carried by the flange and a central bearing sleeve mounted thereon, an eccentric sleeve mounted for rotation within the bearing sleeve and a thrust bearing supporting it, a carriage mounted for rotation upon the sleeve supported by the plate and having a downwardly extending wall adapted to interlock with the housing wall to close the housing, means for rotating the plate, a crushing head carried by the plate and means supported thereby and operated by the eccentric sleeve for operating the crushing head.
- 50 32. In testimony whereof, I affix my signature in the presence of two witnesses this twenty-sixth day of June, 1916.
- 55 33. EDGAR B. SYMONS.
- Witnesses:
NORA B. NELSON,
W. M. SYMONS.
